FASTENER SLIDER

John H. Kohler, Cambridge, Mass., assignor to
 United-Carr Fastener Corporation, Cambridge,
 Mass., a corporation of Massachusetts

Application December 13, 1934, Serial No. 757,338

7 Claims. (Cl. 24—205)

My invention aims to provide improvements in sliders for use with multiple closure fasteners.

In the drawing, which illustrates a preferred form of my invention:—

5 Figure 1 is a top plan view of a multiple fastener assembly including my improved slider;

Fig. 2 is a side view of the slider shown in Fig. 1;

Fig. 3 is a plan view of the slider body before bending into final shape;

10 Fig. 4 is a side view of the slider body as shown in Fig. 3;

Fig. 5 is a view of the inside of the slider before the final forming operation and showing the reinforce;

15 Fig. 6 is a section on the line 6—6 of Fig. 5;

Fig. 7 is a section taken on the line 7—7 of Fig. 2; and

Fig. 8 is a section taken on the line 8—8 of Fig. 1.

20 My improved slider, as illustrated by the accompanying drawing, presents a very strong and simple slider of two-piece construction made and held together without the use of rivets or other fastening means.

25 My improved slider may be made from any suitable material; I prefer to use brass or some similar metal which lends itself readily to drawing and bending operations. The particular form of slider illustrated is formed from sheet metal 30 and has a pair of flat wings 1 and 2 connected by a hollow rib 3. This rib 3 is made of the same material as the wings and extends along each wing as shown in Fig. 3. Along the sides of each plate, I have formed flanges 4, the edges of which

35 are spaced apart from each other a distance great enough to permit the free passage of fastener stringers or tapes between them, at the same time being close enough together to prevent the fastener elements 5 (Fig. 1) from escaping. Since 40 it is necessary in all sliders of this type to have a pair of diverging channels, I have formed from the material of the rib 3 a pair of ears 6 which extend into the space between the wings 1 and 2 as best shown in Figs. 7 and 8.

45 Within the hollow rib I have assembled a reinforcing member 7. This may be made of any suitable material, but I prefer to make it of steel because of the relatively great strength of that metal. This steel reinforcing member is substantially longer than that part of the rib 3 which joins the plates 1 and 2 (Fig. 5); thus it extends part way along each wing and produces a very strong construction. This reinforce may be assembled with the slider proper at any convenient 55 point in the process of construction. I have

found that it is most advantageously inserted when the slider blank has reached the stage shown in Fig. 3 or Fig. 4, at which point it may be placed in the hollow rib just before the ears 6 and the sides 3a of the rib are closed in. Thus when the last-mentioned operation is completed, the reinforce is tightly clamped in the proper position, and is ready to be bent with the neck of the slider when the plates are brought into the proper spaced relationship.

10 The rib 3 is also used to mount the pull tab 8. A convenient method of doing this is to drill or otherwise pierce a hole directly through the rib on the front face of the slider through which the link of the pull tab may be passed. It will be 15 seen from the illustration (Fig. 2) that the rib 3 extends further down the back plate than it does down the front. This is because it is desirable to have the more pronounced projection on the front face to provide a more convenient mounting for the pull tabs and to allow the tab to pivot freely.

20 From the above description it will be seen that my novel slider is exceptionally strong, simple, and easy to manufacture. It has no extra parts 25 to work loose, and all the surfaces bearing on the fastener elements are smooth, making it easy to operate.

25 While I have illustrated and described a preferred form of one embodiment of my invention, it will be understood that I do not wish to be limited thereby, the scope of my invention being best set forth in the following claims.

I claim:—

1. A slider of the class described comprising 35 a pair of spaced apart wings, a rib integral with each wing and connecting said wings together at one end, means between said wings forming diverging channels, and a stiffening member located within said rib for the purpose of strengthening the slider body.

2. A slider of the class described comprising a pair of plate portions, one of said plate portions overlying the other and spaced therefrom a predetermined distance to permit the passage of 45 multiple fastener elements, flanges on the sides of each of said plate portions extending toward the flanges on the other plate portion to prevent the escape of fastener elements, a hollow rib integral with both plate portions and extending 50 continuously from a point on each plate portion along part of its length and connecting the plate portions together, a pair of ears extending from said rib into the space between said plate portions thereby cooperating with said flanges to 55

form diverging channels, and a reinforcing member of relatively hard material assembled in said hollow rib for the purpose of strengthening the slider.

5. A sheet metal slider of the class described comprising a relatively narrow rib member of substantially U-shaped cross-section, a flat plate portion formed integral with said rib member adjacent to each end thereof and each plate part including a portion of said rib member, said rib member being bent at a point between said plate parts whereby said plate parts lie in substantially parallel planes, and a stiffening member located within said U-shaped rib and conforming substantially to the shape thereof for the purpose of strengthening the slider.
10. 4. A sheet metal slider of the class described comprising a pair of similarly shaped plate portions, one of said plate portions overlying the other and being spaced therefrom a predetermined distance to permit the passage of multiple fastener elements, side flanges formed on each plate portion and extending toward the flanges on the other, a hollow rib of U-shaped cross-section formed from the material of said plate portions and connecting said plates together at one end thereof, said rib being curved longitudinally and extending along the outside of each plate for a part of the length thereof, means provided by said rib to form diverging channels between said plates and an independent stiffening member assembled within said hollow rib and conforming substantially to the shape thereof, said stiffening member extending throughout that part of the rib joining the two plates together and along each plate for a part of the length thereof.
15. 5. A sheet metal slider of the class described

comprising a front wing and a back wing, said front wing overlying said back wing and being spaced therefrom a predetermined distance to allow the free passage of multiple fastener elements, fastener-retaining flanges on each wing extending towards the flanges on the other wing, a hollow rib formed from the material of said wings and connecting said wings together, said rib having a rounded end extending from the face of the front plate and a relatively long tapered end on said back wing, a pull member pivotally mounted on said rounded end of the rib, a pair of ears extending from that part of the rib joining the two wings together and said ears extending into the space between said wings thereby cooperating with said flanges to form diverging channels, and a reinforcing member of relatively stiff material assembled within said hollow rib and conforming substantially to the interior contours thereof and extending along each wing for a predetermined distance.

20. 6. A slider of the class described comprising a part shaped to provide a pair of spaced-apart wings, a connecting portion securing said wings together at one end of the slider and a stiffening means formed of a separate piece of material from said connecting portion located entirely within the first-mentioned part.

25. 7. A slider of the class described comprising a part shaped to provide a pair of spaced-apart wings, a connecting portion securing said wings together at one end of the slider and a narrow substantially U-shaped stiffening member formed of a separate piece of material from said connecting portion located entirely within the first-mentioned part adjacent to and in line with the connecting portion.

JOHN H. KOHLER.
